CLAIM

The ornamental design for a medication case, as shown and described.

DESCRIPTION

FIG. 1 is a perspective view of a medication case, shown in an open state;

FIG. 2 is another perspective view thereof in the open state;

FIG. 3 is a perspective view thereof in a closed state;

FIG. 4 is a front view thereof in the open state;

FIG. 5 is a rear view thereof in the open state;

FIG. 6 is a left side view thereof;

FIG. 7 is a right side view thereof;

FIG. 8 is a top view thereof in the open state;

FIG. 9 is a bottom view thereof in the open state; and,

FIG. 10 is a perspective view of the medication case, shown with the inner case and outer case completely separated for ease of disclosure.

The broken lines in the drawings depict portions of the medication case and form no part of the claimed design.
